UNITED STATES PATENT OFFICE.

CHARLES L. HEISLER, OF SCHENECTADY, NEW YORK, ASSIGNOR, BY MESNE ASSIGNMENTS, TO THE WELDLESS ROLLED RING COMPANY, A CORPORATION OF OHIO.

BAND-ROLLING MACHINERY.

Application filed July 27, 1920. Serial No. 399,415.

To all whom it may concern:

Be it known that I, CHARLES L. HEISLER, a citizen of the United States, residing at Schenectady, in the county of Schenectady, 5 and State of New York, have invented certain new and useful Improvements in Band-Rolling Machinery; and I do hereby declare the following to be a full, clear, and exact description of the same, reference being had 10 to the accompanying drawings, forming part of this specification.

My invention relates to improvements in machines for rolling bands of metal, particularly bands of copper for use on shells 15 intended to be fired in the larger caliber Army and Naval guns; and the objects of my improvements are: first, to provide a novel set of gearing for the rolls whereby smoother action is secured than can be obtained with the present equipment; second, to provide means for the water-cooling of the various parts without the disadvantage common to all machines with which I am familiar, which disadvantage consists in the 20 fact that the cooling water is permitted to come into contact with the ingot of metal being rolled; third, to render more simple and efficient the reciprocating carriage for permitting insertion of the blank or hollow 25 ingot on the mandrel; fourth, to provide an improved mandrel; and fifth, to provide a more substantial support for the heavy duty mandrel and to improve generally the connections of this element of the machine.

With the above and other objects in view, 35 the invention consists in certain combinations, arrangements and constructions of parts hereinafter described in their preferred form and particularly pointed out in 40 the claims at the end of the specification.

The various objects of my invention are obtained by the mechanism illustrated in the accompanying drawing, in which,—

Figure 1 is a central, longitudinal, vertical section showing the entire machine, including the water cooling pipes and the driving pulley.

Fig. 2 is a front elevation of the same with the driving pulley omitted.

50 Fig. 3 is a rear end elevation partly in section particularly designed to illustrate the gearing and the piston controlled hinge arrangement of the upper or top roll, and

therefore omitting such features as are unnecessary for the above object.

Fig. 4 is a transverse vertical sectional view taken through the center line of the pressure cylinder.

Fig. 5 is a horizontal sectional view taken on line 5—5 of Fig. 3.

Fig. 6 is a horizontal sectional view taken on the line 6—6 of Fig. 3.

Fig. 7 is a vertical sectional view taken on line 7—7 of Fig. 1.

The bed 8 of the machine is securely bolted to front and rear legs 9 and 10 which, in turn, are fastened to the floor or concrete base by means of bolts passing through the flanges of the extended feet 11 of the legs 9 and 10. This bed is generally rectangular in plan and in cross section, but is provided with a pair of posts 12 rising from the rear thereof and co-operating with the hinge caps 13 to form bearings for the hinge shaft 14 which extends practically the length of the machine and carries on its right hand end, as viewed in Fig. 5, the hinge shaft gear 15. The bed is also extended at the rear and side to form a gear housing 16 and at the front to form a box bracket 17 for the pressure cylinder 18 which controls the raising and lowering of the top roll 19, this roll being carried by a spindle 20 rotatably mounted in the top roll housing 21, the latter being a casting of considerable size and forming in effect a lever pivotally mounted on hinge shaft 14 as a fulcrum by bearings 22 in extensions 23 and 24, and movable about that shaft by virtue of the connection between arm 25 and the rod 26 of the piston 27 in pressure cylinder 18.

At the right hand side, as viewed in Fig. 5, the top roll housing is enlarged to form a housing 28 for the two similar meshing gears 15 and 29, the former being rotatably mounted on the hinge shaft 14, while the latter is keyed to the top roll shaft or spindle 20. This housing 28 is open at its end to permit of easy access to the inclosed gears, but is provided with a removable cover plate 30 so positioned as to just clear the gear cover 31 which co-operates with the extension 16 to protect the lower gears 32 and 33, the former keyed to the main drive shaft 34 and the latter rotatably mounted (in a manner hereinafter described) on a

stud shaft 35 and held in angular position in the housing 16 by a key 17' and held against longitudinal movement by the head 36 and by a cotter pin or wedge 37 bearing 5 against the wall 38 of the bed 8.

The top roll 19 is held in angular position on spindle 20 by a pair of keys 40, and is held against a shoulder 41 on the spindle by means of a washer 42 secured to the spindle 10 by a hollow cap screw 43 fitting in a tapped hole 44 extending axially of the spindle to a transverse hole 45 drilled through the spindle so as to communicate with an annular well 46 in the interior of the roll 19. 15 Cooling water from pipe 47 which forms a water-tight connection with cap screw 43 passes through tapped hole 44 to the passage in the spindle and from there into the cooling well 46, the latter having four equi-spaced exits 48, discharging the water into a suitable receptacle (not shown).

Power is received by driving pulley 50, which, like driving pinion 32, is keyed to a reduced section of the main driving shaft 34 25 and held against a shoulder 51 thereon by the usual washer 52 held in place by connecting screw 53. The driving pinion 32 drives gear 33 keyed to the extended sleeve 54 of a pinion 55 freely rotatable on stud shaft or 30 pin 35, and pinion 55 drives the freely rotatable gear 15, and through it, the gear 29 keyed to the top roll shaft, these connections, it will be noted, causing the main drive shaft and the top roll shaft to rotate in opposite 35 directions, and, since these two shafts are in the same vertical plane, to cause cylinders mounted thereon to co-operate so as to roll a body placed between them.

The lower cylinder in the construction illustrated is a mandrel, 60, extending preferably about as far beyond the upper roll as the latter extends beyond the edge of the bed, and having its inner end tapered, as at 61, to form a driving fit with the socket 62, formed integral with the main driving shaft 34, connecting bolt 53 extending into a tapped hole 63 in the mandrel shaft, thus securing the drive and mandrel shafts together, as well as securing same in longitudinal adjustment by the contact of shoulder 64 on the mandrel socket 62 with the abutment 65 on the drive shaft casing 66, the latter being an integral portion of the bed 8, and forming one wall of the socket chamber 67, the upper wall of which is a removable cover plate 68 permitting of ready access to the coupling. The bearing surfaces for the drive shaft and for the mandrel shaft are preferably formed of a plurality of sections of semi-cylindrical bushings 69 held in place by integral lugs 70 fitting in appropriate recesses 71 in the casing 66, the mandrel cap 72 and in the spindle cap 73, these two caps being secured to the casing 66 by 65 means of stud bolts 74, similar to the stud

bolts 75 which secure the hinge shaft clamps 13 to their seats 12.

Legs 9 and 10 each have an upper platform 80 machined on either side as at 81 to receive the bed 8 and provided on the 70 lower side with two enlarged bearings 82 to serve as supports for the guide rods 83 which reciprocate within these bearings. A reciprocating guide 84 is mounted on the front end of each of the guide rods 83 and 75 includes a pair of legs 85 extending upwardly from the guide rods and terminating in bearings 86 loosely receiving the studs 87 carried by the guide plate 88. An additional stud carried about centrally of plate 88 80 is received by an extension 89 connected to the legs 85 by means of a cross piece 90 which extends forwardly as at 91 and ends in a bracket 92 to which is fitted a cap piece 93 to provide for the securing of the water 85 cooling pipe furnishing cooling water to the mandrel 60. The guide plate 88 is of considerable width and tapers toward the top, the vertex of such taper being cut away to provide a circular hole which loosely 90 engages the mandrel and serves to hold the band in place on the mandrel.

At their rear ends just inside of the rear leg 10 the guide rods 83 are connected together by a cross head 94 which is provided 95 with clips 95 which hold the rods against seats 96 on the cross head, correct positioning being secured by means of dowels 97 entering the seats and the rods. Cross head 94 has an upward extension 98 at its rear end which receives the reduced end 99 of a piston rod 100 connected at the other end to a piston in cylinder 101. This cylinder 101 is provided with a rear head 102 having the usual gland and stuffing, as shown, and 105 having a front head 103 which forms the support for the cylinder and piston rod. This front head is bolted to the front leg 9 by means of an integral bracket 104 bifurcated as at 105 to clear a slot (not shown) 110 and to provide room for the head of bolt 107, movable in said slot.

A guide roll plate 110, cut away centrally, as at 111, to provide for reception of the mandrel, is bolted to the front leg 9 and 115 also to the bed 8, and carries a plurality of band guide roll carriers 112 which support and guide the band when in its finished position. These guide rolls are adjustable on the plate 110 by means of screws 114 120 threaded into lugs 115 and being held in adjusted position by means of the lock nuts 116. When the lock nut is released the screw 114 may be adjusted to bring the roller 117 into proper position by means of the squared 125 end 118 of the screw and may be secured in such position by the lock nut 116.

The top roll housing 21 ends at the front in an open chamber for the top roll, the chamber having an open bottom, a top wall 130

120, a back wall 121, and side walls 122, the latter having finished channels 123 therein to slidably receive brackets 124 carrying at their lower ends the guide rolls 125. These brackets are adjusted vertically by nuts 126 on studs 127 carried by the top roll chamber, and are held in such adjusted position by the headed bolts 128 carried by the side walls 122 and passing through appropriate slots 129 in the brackets 124 and having the usual washers 130 and nuts 131.

10 Arm 25, which is connected to piston rod 26 by means of pin 133 held in the bifurcated ends of the arm by a cotter 134, is threaded near its junction with the casing 21 to receive a feed screw 135 operated by a hand wheel 136 to control the rate of reduction of the thickness of the band. Adjustable gages 137 threaded in bushings 138 may be 20 operated by means of their squared ends 139 to bear against the upper surface of the mandrel cap 72, as best shown in Fig. 4. A similar gage 140 bears against the cap 73 and is locked in adjusted position by a nut 141 25 similar to the nut bearing the same numeral on gage 137.

Referring now to Fig. 1; cooling water enters pipe 150 and passes from there to the top roll as previously described and also 20 to a vertical port 151 in the back wall 121 of the open chamber of the top roll housing, this port being in communication with a horizontal port 152 through an annular groove or channel 153 which surrounds the 25 front bushing of the top roll shaft 20. The port 152 in the lower section of the top roll housing is closed by a plug at the front end and has an orifice 154 at the inner end communicating with a basin 155 in the mandrel cap draining through one or more similar 30 ports 156 on either side of the mandrel 60 to a water chamber 157 discharging through pipe 158 threaded into pipe plug 159.

What I claim is:

45 1. In a band rolling machine, a rotatable mandrel, an auxiliary shaft, a frame having widely separated bearings pivoted thereon, a pressure roll shaft rotatably mounted in said frame parallel to and substantially vertically above said mandrel, and gearing connecting said pressure roll and said mandrel in all positions of said frame.

2. In a band rolling machine, a rotatably mounted power shaft, a mandrel secured to 55 said power shaft, a supplemental frame, a shaft carried by said supplemental frame, a roll on said shaft, a set of gears constantly in mesh for transmitting power from said power shaft to said shaft, and means for moving said shaft with respect to the axis of said power shaft and mandrel.

3. In a band rolling machine, a rotatable mandrel, an auxiliary shaft, a frame having widely separated bearings pivoted thereon, a 60 pressure roll shaft rotatably mounted in

said frame parallel to and substantially vertically above said mandrel, a shaft in horizontal alinement with said mandrel and in vertical alinement with said auxiliary shaft, and gearing on said shafts and on said mandrel for connecting said mandrel and each of said shafts for simultaneous movement in all positions of said frame. 70

4. In a band rolling machine, a frame, a power shaft rotatably mounted in said frame, 75 a mandrel connected coaxially to said power shaft, a housing pivoted to said frame, a pressure roll mounted in said housing, means for moving said housing about its pivot, and means for operatively connecting said mandrel and said pressure roll. 80

5. In a band rolling machine, a frame, a power shaft mounted in said frame, an auxiliary shaft rotatably mounted in said frame with its axis parallel to the axis of said power shaft, a supplemental frame pivotally mounted on said auxiliary shaft, a top roll shaft mounted in said supplemental frame and gears mounted on each of said shafts operatively connecting all three of 85 said shafts in all positions of said supplemental frame, means for moving said supplemental frame about its pivot, means adjustable with respect to said top roll shaft and movable with said supplemental frame 90 for guiding a band being rolled, and independent means carried by said frame and adapted to contact with the finished rolled ring. 95

6. In a band rolling machine, a frame, a hollow mandrel mounted in said frame to revolve about a fixed axis, a pivot shaft mounted on said frame, a hollow pressure roll pivotally and rotatably carried by said pivot shaft with its axis constantly parallel 100 to the axis of said pivot shaft and the axis of said mandrel, operative means for driving said pressure roll and said mandrel at a relatively fixed rate with respect to each other, means for altering the distance between the axis of said pressure roll and said mandrel whereby a band may be rolled, and means for conducting a fluid to said pressure roll and said mandrel and for discharging such cooling fluid in a direction parallel 105 to said axes. 110

7. In a band rolling machine, a frame, a power shaft mounted in said frame, a tapered mandrel rotatably mounted in said frame coaxially with said power shaft, 120 means for operatively connecting said mandrel and said power shaft, a top roll cooperating with said mandrel to roll a band therebetween, and rollers adjustable on said frame for supporting said band when it has 125 been rolled to the desired size.

8. In a band rolling machine, a frame, a mandrel rotatably mounted in said frame, a pressure roll pivotally and rotatably carried 130 on said frame, power connections between

said mandrel and said pressure roll, means for altering at will the distance between the axis of said pressure roll and said mandrel, a reciprocating carriage mounted on said frame, and means carried by said carriage for maintaining a band in proper position between said mandrel and said pressure roll during the rolling operation said carriage withdrawing said means from said mandrel 10 at the close of such operation.

9. In a band rolling machine, an oblong frame, a mandrel rotatable about a fixed axis on said frame, a supplemental frame pivoted near one long side to the main frame and carrying a pressure roll adapted to cooperate with said mandrel to roll a band, adjustable guide rolls mounted on said supplemental frame, and means pivotally secured to the opposite long side of said supplemental frame for moving same about its pivot on the main frame.

10. In a band rolling machine, a main frame, a supplemental frame pivoted in said main frame, a mandrel pivotally mounted 25 in said main frame and having a cavity therein directed outwardly from said frame, a pressure roll mounted in said pivoted supplemental frame and having a plurality of discharge passageways therein directed outwardly from said frame, means for moving said pressure roll with respect to said mandrel, and means for delivering cooling fluid to said pressure roll and to said mandrel during relative movements of these parts.

30 11. In a band rolling machine, a mandrel, a frame movable with respect to the axis of said mandrel, a pressure roll mounted in said frame and adapted to cooperate with said mandrel to roll a band, a guide roll 35 adjustably carried by said frame and adapted to cooperate with said mandrel to roll a band, and an independent guide roll adapted to contact with the band when same has been rolled to the desired diameter.

40 45 12. In a band rolling machine, a mandrel, a frame movable with respect to the axis of said mandrel, a pressure roll rotatably mounted in said frame and adapted to co-

operate with said mandrel to roll a band, a plurality of guiding rolls adjustably 50 mounted on said frame and a plurality of guide rolls adapted to contact with the band when the diameter of same has been increased to a predetermined size.

13. In a band rolling machine, a hollow 55 adjustable mandrel, a pipe adapted to direct a cooling fluid into the hollow of said mandrel, and means movable axially of said mandrel for supporting said pipe.

14. In a band rolling machine, a hollow 60 adjustable mandrel, a pipe adapted to direct a cooling fluid into the hollow of said mandrel, means movable axially of said mandrel for supporting said pipe, and a band retaining plate yieldingly carried by said means. 65

15. In a band rolling machine, an oblong frame, a mandrel rotatably mounted near one long face thereof, a roll adapted to cooperate therewith to roll a band, means for keeping the axes of said roll and mandrel 70 parallel and a rotatable shaft parallel to said axes furnishing the support for said means.

16. In a band rolling machine, a frame, a driven shaft rotatably mounted therein, a 75 supplemental frame pivoted on said shaft, a shaft rotatably mounted in said supplemental frame, and a pair of constantly meshing gears one of which is carried by said driven shaft and the other of which is carried by the shaft rotatably mounted in the supplemental frame.

17. In a pressure roll for a band rolling machine, characterized by the provision of an annular passageway, a central axial passageway communicating therewith, and a plurality of passageways connecting said annular passageway with a side face of said pressure roll whereby cooling fluid delivered to said central axial passageway will be discharged in streams parallel to said entrance but in opposite direction. 85 90

CHARLES L. HEISLER.
